Oct. 10, 1933.

E. H. SARGENT

1,929,757

FOOTBALL GAME

Filed Feb. 23. 1932

3 Sheets-Sheet 1

Oct. 10, 1933.

E. H. SARGENT

1,929,757

FOOTBALL GAME

Filed Feb. 23, 1932

3 Sheets-Sheet 2

Oct. 10, 1933.

E. H. SARGENT

1,929,757

FOOTBALL GAME

Filed Feb. 23, 1932

3 Sheets-Sheet 3

Inventor
Edgar Haskell Sargent
By Fred G. Leland
his Atty

UNITED STATES PATENT OFFICE

1,929,757

FOOTBALL GAME

Edgar Haskell Sargent, Evanston, Ill.

Application February 23, 1932. Serial No. 594,439

10 Claims. (Cl. 273—94)

The present invention pertains generally to football games. More particularly, the invention pertains to that type of football game which is designed to be played by two contestants or players and comprises a board in the form of a football field and two teams of eleven men each.

One object of the invention is to provide a football game of this type which follows, and closely resembles in play, the outdoor game of football, and is a closer approach to the latter than previously designed football games, in that the men which form the two teams are designed to be pushed over the board in the execution of plays by means of pushers in the hands of the two contestants.

Another object of the invention is to provide a football game of the last mentioned character in which the men embody flat bases whereby they are supported in substantially upright positions, and are so constructed and balanced that by manipulation of the pushers upon the bases, they may be tilted or upset for tackling, diving or blocking purposes.

Another object of the invention is to provide a football game of the type under consideration in which the pushers for manually manipulating the men over the board have thin, blade-like extensions at the front or working ends thereof for insertion between the board and the bases of the men, and the board is formed of cloth or fabric so that it yields to such an extent that the extensions of the pushers may be readily shifted beneath the bases to form connections between the men and the pushers whereby the men may be readily tilted or tipped in response to manipulation of the pushers.

A further object of the invention is to provide a football game of the aforesaid type in which each team embodies a man which may be substituted for a backfield man, during the execution of a kicking play, and is so constructed that one leg is free with respect to the base and may be used, by flipping the finger thereagainst, to kick an object representing a ball.

A still further object of the invention is to provide a football game of the type and character heretofore specified wherein the bodies of the men are inclined forwardly so that they are properly constructed and arranged for tackling purposes and in order that in the execution of forward pass plays, the ball may be placed thereagainst and flipped with the finger towards an objective.

In addition, it is contemplated as one of the objects to the invention to provide a football game which is generally of new and improved construction and may be manufactured at a low and reasonable cost, and in which the play is determined solely by manual manipulation of the men.

Other objects of the invention and the various characteristics and features of the present game will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a perspective of a football game embodying the invention;

Figure 2 is a perspective showing the manner in which the men are manipulated or moved by the pushers in scrimmage plays;

Figure 3 is a plan view of a blank of the type which is used in connection with the formation of the men;

Figure 4 is a side view illustrating the manner in which a man may be manipulated by a pusher to tackle a man of the opposing team;

Figure 5 is a perspective of one of the kickers;

Figure 6 is a perspective showing the manner in which the kicker is manipulated by a flip of the finger to effect a kick of the ball; and

Figure 7 is a perspective illustrating the manner in which a forward pass may be made by flipping the ball with the finger across the back of one of the men.

The football game which forms the subject matter of the invention is designed to be played by two contestants or players and consists of a board 8 and a team A of men and a team B of men. The board is adapted to be laid upon a card table 9 or like supporting member, and is formed of cloth or fabric so as to form a slightly resilient supporting surface for the men. It is square in conformation and is numbered and lined on the top surface thereof so as to represent a football field. Elastic bands 10 serve to keep the board taut and connected to the table 9. These bands extend across the corners of the board and are adapted to underlie the corners of the table, as illustrated in Figure 1 of the drawings. A pair of H-shaped members 11 form goal posts for the field. These members are located beyond the end zones of the field similarly to the goal posts for a regular football playing field, and have braces or supports 12 at the lower ends thereof so as to hold them in an upright position. During play of the game, the goal post-forming members 11 are preferably moved to one side of the playing field so as not to interfere with manipulation of the men.

The team A consists of seven linemen 13, four backfield men 14 and a substitute kicker 15. The linemen 13 correspond to the center, guards, 10 tackles and ends of a regular football team. The backfield men 14 are similar in design and construction to the linemen 13 and correspond to the half-backs, quarter-back and full-back of a regular team. With the exception of the substitute kicker 15, each of the men which compose the team A is made from a blank 16 (see Figure 3) and consists of a flat, rectangular base 17 and a body 18. The latter is formed and designed so that it simulates a football player in 20 appearance and embodies a pair of legs 19, a trunk 20, a pair of arms 21 and a head 22. One of the legs 19 extends rearwardly from the trunk 20 to one of the rear corners of the base 17, and is attached to a flap 23 which extends upwardly 25 from, and is formed integrally with, the rear end of the base. The other leg extends forwardly from the trunk 20 and embodies a foot 24. The latter is cemented or otherwise secured to the front corner of the base which is diagonally opposite the corner to which the rearwardly extending leg extends. The knee parts of the legs 19 are bent as at 25, so as to give them a lifelike appearance. The trunk 20 and the head 22 are coplanar and are inclined upwardly and forwardly so that the center of mass thereof is located 35 over the foot 24. The arms 21 are bent at the shoulders and elbows so that they extend forwardly in the manner illustrated in the drawings. The blank 16 is cut or stamped from any suitable 40 type of comparatively tough sheet material, such, for example, as strawboard, and is shaped to form the base 17, the body-part 18 and the flap 23. The flap 23 is cut at one end thereof so as to form the foot 24 and disconnect the latter from 45 the base. It is bent on the line 23^a so that it extends vertically and is colored or designed at the other end thereof so as to form a foot for the leg which extends rearwardly from the trunk 20. The foot 24, after being severed or cut from 50 the base, is cemented or otherwise secured in the proper position on the top face of the base. The kicker 15 is adapted, during kicking plays, to be substituted for one of the backfield men 14. It is exactly the same in construction and design 55 as the linemen 13 and the backfield men 14 of the team A except that the forwardly extending leg thereof is not attached to the base in order that it may be used, as hereinafter described, to kick a flat, oval-shaped member 26 representing a ball. 60 The linemen and backfield men of the team A are adapted to be moved or shifted over the board 8 by a pusher 27. The latter is adapted to be held by one of the contestants or players and embodies at the front end thereof an abutment-forming 65 surface 28 and a comparatively thin, blade-like extension 29. The abutment-forming surface 28 is adapted to be brought into engagement with the flaps 23 when the pusher is manipulated so as to shift the men. The extension 29 underlies the abutment-forming surface 28 and is adapted to be inserted under the bases so that it is possible, during pushing of the men by the pusher, to upset the men for tackling or blocking purposes. By virtue of the fact that the men are 70 constructed so that the legs thereof are connected to diagonally opposite corners of the bases, and the trunks of the body-parts are inclined forwardly and upwardly, the men are so balanced that they may be readily upset. To advance a man, the extension 29 of the pusher is inserted under the base and the abutment-forming surface 28 is brought into contact or engagement with the flap 23. Thereafter, the pusher is moved forwardly with the result that the man is caused to slide over the board. If it is desired to have the man dive forwards or sideways for blocking or tackling purposes, the pusher is raised so as to upset the man in the proper direction. The ends and backfield men of the team A have marked on the bases and backs thereof different numerals or indicia 30 so that they may be identified in connection with the play.

The team B consists of seven linemen 31, four backfield men 32 and a substitute kicker (not shown), and is manipulated by the other contestant or player by means of a pusher 33. The linemen and backfield men of the team B are similar in construction and design to the linemen and backfield men of the team A, and consist of 100 substantially flat, rectangular bases 34 and body-parts 35. They are preferably colored differently than the men of the team A so that the contestants or players may readily distinguish the two teams. The pusher 33 is similar in design 105 to the pusher 27 and is provided at the front end thereof with an abutment-forming surface 36 and a thin, knife-like extension 37. The ends and backfield men of the team B are provided with different numerals or indicia 38 on the bases and 110 backs thereof.

The game is designed to follow as closely as possible the rules and play of regular football. If desired, the game may be played as follows:

Kick-off

115

A coin is first tossed to determine which contestant or player has the choice of kicking or receiving. The contestant having the team which is required or has been selected to kick off, lines 120 his men on their own forty yard line. The contestant or player having the team which has been required or selected to receive, arranges his men in any desired formation on or behind their own forty-five yard line. The contestant having the 125 kicking team substitutes his kicker for one of the backfield men and effects a kick of the ball into the territory of the opposing or receiving team by first placing the ball on the board and against the free or swinging leg of the kicker, and then 130 flipping the leg by the finger. The latter action serves to project the ball down the field. In the event that the ball strikes one of the men of the receiving team, it is presumed to be caught by the man that is struck. If the ball lights within the 135 field without touching one of the men of the receiving team, the contestant or player having charge of such team moves, by manipulation of his pusher, one of the men so that it touches the ball in order to have that man effect the catch. If the ball lights in the end zone, the contestant 140 having the receiving team may elect to have one of his men run with the ball or to put the ball in play on his own twenty yard line. After kicking the ball, the contestant having the kicking team 145 replaces the kicker for the man for whom the kicker was substituted and when ready, gives the signal to start play. The instant the signal is given, both players move their men with the pushers; the defensive player or contestant at- 150 tempting to move his men down the field so as to tackle the offensive man having the ball, and the offensive contestant attempting to block out the men of the defensive team, and to advance the ball carrier down the field as far as possible. When the ball carrier is blocked or upset by a man of the defensive team, the play is concluded and the ball is deemed to be downed at the farthest point to which the ball carrier has advanced. In manipulating the defensive team, the contestant or player having such team may, by manipulation of his pusher, upset his men so as to block or knock down the men of the defensive team, that is, the team that has kicked the ball. In manipulating the men of the defensive team, the contestant or player having such team is able to tackle or bring down the ball carrier by moving one or more of his men into the path of movement of the ball carrier and then upsetting his man or men so as to knock the ball carrier to the board.

Scrimmage

After the kick-off, the contestant having the defensive team arranges his linemen so that the bases thereof are on, or in back of, the line of scrimmage, and places his backfield men in any desired defensive position. Thereafter, the contestant having the offensive team arranges his linemen in front of the linemen of the defensive team and positions his backfield men in any desired position for the execution of a preconceived play. In order not to handicap the defense, the contestant having the defensive team is permitted to rearrange his linemen and backfield men after arrangement and positioning of the men of the offensive team. A play is started by the contestant having the offensive team calling the number of the backfield man to whom the ball is supposedly passed by the center and immediately thereafter saying the word "go". At the word "go", both contestants are permitted to move their men, the defense attempting to tackle the man of the offensive team whose number has been called, and the offense attempting to block the defensive men and to advance the runner. In executing the play, the contestants move their men, one at a time, by manipulating the pushers, as hereinbefore described and as shown more particularly in Figure 2 of the drawings. When the man of the offensive team who has been designated as the ball carrier is blocked out or tackled by a man of the defensive team, the play is concluded.

Forward pass

A forward pass may be made at any time and from any formation by the offensive team. The pass play is started by the contestant having the offensive team calling out the number of one of the backfield men who is supposed to make the pass, and announcing "go". At the word "go", the two contestants start to move their men the same as though a scrimmage were taking place. In order to prevent the supposed passer from being tackled, the contestant having the offensive team says "pass". This informs the contestant having the defensive team that the player to whom the ball was supposedly passed at the start of the play, is to pass the ball. After the word "pass", the men eligible to receive passes (ends and backfield men) are moved into a position wherein the contestant having the offensive team desires to have the pass completed. At the same time, the contestant having the defensive team moves his men into defensive positions and so as to upset, if possible, the expected receivers of the pass. When the man desired by the offense to receive the pass is moved to the desired location or position, the contestant having the offensive team calls the number of the intended pass receiver and announces "pass" to indicate that the ball is in the course of travel from the passer to the receiver. Immediately upon announcing the number of the receiver and the word "pass", play is discontinued by both contestants. The contestant having the offensive team then places the ball on the back of the passer, as shown in Figure 7 of the drawings, and flips the ball with the fingers towards the receiver. If the ball hits the receiver, the pass is deemed to be completed. If the receiver is missed but an opponent, that is, a man of the defensive team, is struck, the pass is deemed to be intercepted. If the ball touches the ground before touching either the pass receiver or an opponent, the pass is deemed to be incomplete. By virtue of the fact that the heads of the men are coplanar with the trunks, the ball may be flipped with considerable accuracy. In the event that the pass is intercepted, play is resumed when the contestant executing the pass takes his pusher in his hand. Under such circumstances, the contestant of the intercepting team endeavors, by manipulation of his pusher, to advance, as far as possible, the man having intercepted the ball.

Punt

A punt is executed by the contestant with the offensive team calling the number of the backfield man to whom the ball is supposedly passed from the center and announcing "go". At the word "go", both contestants start to move their men and the contestant having the defensive team may tackle the offensive player whose number has been called until the contestant having the offensive team calls "kick". After the word "kick", the contestant having the offensive team, that is, the team that is executing the kick, moves his men down the field to cover the receiver of the kick, and at the same time the contestant having the defensive team moves his men into position to block the kick. The kick itself is effected by the contestant with the kicking team substituting his kicker for the man whose number was first called. After placement of the kicker on the spot formerly occupied by the removed man, the kicker's right leg is held in a raised position, as shown in Figure 6 of the drawings, and the ball is placed on the foot. By snapping the kicker's leg with the fingers, the contestant with the kicking team causes the ball to be projected down the field. The play is continued from this point as outlined in connection with the kick-off.

Drop kick

A drop kick is effected similarly to a punt, except that the ball is placed on the ground as in the kick-off instead of on the kicker's raised leg, and is directed over the opponent's goal posts.

The play may be made to follow closely the rules and play of outdoor regular football, and is based upon strategy and manual manipulation of the men instead of chance. If desired, the game may be used to demonstrate plays in connection with the coaching of a regular football team.

The herein described game may be manufactured at a low and reasonable cost, inasmuch as 80

85

90

95

100

105

110

115

120

125

130

135

140

145

150

the men which comprise or form the two teams are of exceedingly simple construction.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a game of the character described, the combination of a board with a football field marked thereon, and a plurality of men forming two teams and adapted to be pushed by the players of the game at random and in any and all directions over the board in connection with the execution of plays similar to those of the outdoor game of football, said men consisting of flat, substantially rectangular bases, slideable over the board and body-parts extending upwardly from the bases and simulating in appearance regular football players, and having said body-parts arranged and constructed so that the centers of mass thereof overlie the front portions of the bases in order that during pushing, the men may be readily upset for blocking or tackling purposes by tilting them forwardly.

2. In a game of the character described, the combination of a board with a football field marked thereon, and a plurality of men forming two teams and adapted to be pushed by the players of the game at random and in any and all directions over the board in connection with the execution of plays similar to those of the outdoor game of football, said men consisting of bases slideable over the board and body-parts extending upwardly from the bases, and being balanced and constructed so that they may be readily upset during pushing thereof for blocking or tackling purposes, the men of the two teams that form the backfield men having different numerals or indicia on the bases thereof so that they may be selectively designated by the players as ball carriers.

3. In a game of the character described, the combination of a board with a football field marked thereon, and a plurality of men forming two teams and adapted to be pushed by the players of the game at random and in any and all directions over the board in connection with the execution of plays similar to those of the outdoor game of football, said men consisting of bases slideable over the board and body-parts extending upwardly from the bases and simulating in appearance regular football players, and having said body-parts so arranged and constructed that the centers of mass thereof overlie the front portions of the bases in order that during pushing of the men by the players the men may be readily upset for blocking or tackling purposes by tilting them forwardly, the men of the two teams forming the ends and backfield men having different numerals or indicia on the bases and backs of the body-parts in order that they may be selectively designated by the players as ball carriers or in connection with the plays.

4. In a game of the character described, the combination of a board with a football field marked thereon, and a plurality of men forming two teams and adapted to be pushed by the players of the game at random and in any and all directions over the board in connection with the execution of plays similar to those of the outdoor game of football, said men consisting of bases slideable over the board and body-parts extending upwardly from the bases, and being balanced and constructed so that they may be readily upset during pushing thereof for blocking or tackling purposes, certain of the men designed to play in the backfields of the teams having the body-parts thereof formed with flat, forwardly and upwardly inclined surfaces whereby a flat, ball simulating member may be placed thereagainst and flipped by the fingers in the execution of forward pass plays.

5. In a game of the character described, the combination of a board with a football field marked thereon, and a plurality of men forming two teams and adapted to be pushed by the players of the game at random and in any and all directions over the board in connection with the execution of plays similar to those of the outdoor game of football, said men consisting of bases slideable over the board and body-parts extending upwardly from the bases and simulating in appearance regular football players, said bodyparts being balanced and arranged with respect to the bases so that the men may be readily upset, during pushing thereof, for blocking or tackling purposes, and having the backs thereof inclined forwardly and rearwardly so that forward pass plays may be executed by placing a flat, ball simulating member thereagainst and flipping it with the fingers.

6. In a game of the character described, the combination of a board with a football field marked thereon, a plurality of men forming two teams and adapted to be pushed by the players of the game at random and in any and all directions over the board in connection with the execution of plays similar to those of the outdoor game of football, said men consisting of bases slideable over the board and body-parts extending upwardly from the bases and simulating in appearance regular football players and having said body parts arranged and constructed so that the centers of mass thereof overlie the front portions of the bases in order that during pushing, the men may be readily upset for blocking or tackling purposes by tilting them forwardly, and pushers adapted to be held by the players and used in connection with pushing and forward tilting of the men.

7. In a game of the character described, the combination of a board with a football field marked thereon, a plurality of men forming two teams and adapted to be pushed by the players of the game at random and in any and all directions over the board in connection with the execution of plays similar to those of the outdoor game of football, said men consisting of bases slideable over the board and body-parts extending upwardly from the bases and being balanced and constructed so that they may be readily upset by pushing thereof for blocking or tackling purposes, and pushers for pushing the men adapted to be held by the players and having thin, blade-like parts at the front ends thereof for disposition under the bases and use in connection with upsetting of the men.

8. In a game of the character described, the combination of a board with a football field marked thereon, a plurality of men forming two teams and adapted to be pushed by the players of the game at random and in any and all directions over the board in connection with the execution of plays similar to those of the outdoor game of football, said men consisting of flat, substantially rectangular bases slideable over the board and provided with upstanding flaps at the rear ends thereof and body-parts extending upwardly from the bases and simulating in appearance regular football players, and having said body parts so arranged and balanced with respect to the bases that during pushing of the men by the players they may be readily upset for blocking or tackling purposes, and pushers for use by the players in pushing the men adapted to be held in the hands of the players and having flat surfaces at the front ends thereof for engagement with the flaps at the rear ends of the bases of the men.

9. In a game device of the character described, the combination of a slightly resilient, fabric board with a football field marked thereon, a plurality of men forming two teams and adapted to be pushed by the players of the game at random and in any and all directions over the board in connection with the execution of plays similar to those of the outdoor game of football, said men consisting of bases slidable over the board and body-parts extending upwardly from the bases and being balanced and constructed so that they may be readily upset during pushing thereof for blocking and tackling purposes, and pushers for pushing the men adapted to be held in the hands of the players and having thin, blade-like extensions at the front ends thereof for insertion between the board and the aforesaid bases and use in upsetting the men.

10. In a game of the character described, the combination of a board with a football field marked thereon, and a plurality of men forming two teams and adapted to be pushed by the players of the game at random and in any and all directions over the board in connection with the execution of plays similar to those of the outdoor game of football, said men consisting of flat, substantially rectangular bases slidable over the board and body parts extending upwardly from the bases and simulating in appearance regular football players, the legs of the body part of each man extending one forwardly and one rearwardly and secured to diagonally opposite corners of the base and being bent and arranged so that the weight or center of mass of the body part is substantially over the forwardly extending leg in order that the man may be readily upset for blocking or tackling purposes.

EDGAR HASKELL SARGENT. 100

30

105

35

110

40

115

45

120

50

125

55

130

60

135

65

140

70

145

75

150